[57] CLAIM

The ornamental design for an electric guitar body, as
shown and described.

DESCRIPTION

FIG. 1 is a front perspective view showing my new
design for an electric guitar body;

FIG. 2 is a top plan view thereof;

FIG. 3 is a front elevational view thereof;

FIG. 4 is a side elevational view taken from the left side
of FIG. 2;

FIG. 5 is a bottom plan view thereof;

FIG. 6 is a rear elevational view thereof; and,

FIG. 7 is a side elevational view taken from the right
side of FIG. 2.
